(57) **CLAIM**

The ornamental design for a camp cart as shown and described.

DESCRIPTION

FIG. 1 is an enlarged front elevational view of a camp cart showing my new design;

FIG. 2 is an enlarged rear elevational view thereof;

FIG. 3 is a left side view thereof;

FIG. 4 is a right side view thereof;

FIG. 5 is a perspective view thereof;

FIG. 6 is a second perspective view thereof; and,

FIG. 7 is a third perspective view thereof.
